COUCH CONSTRUCTION

Lewis E. Mitzenmacher, Los Angeles, Calif., assignor to David Erenberg, Los Angeles, Calif.

Application February 1, 1951, Serial No. 208,917

13 Claims. (Cl. 5—18)

1

This invention relates to couch construction and to leg construction.

For some purposes, such as sleeping, a couch having a substantially horizontal seating surface is preferred. For other purposes, such as sitting, a couch having a seating surface which slopes slightly downwardly, toward the rear, is preferred. In conventional couches, the seating surface is fixed in either horizontal or sloped position.

An object of my invention is to provide a couch with adjustable rear or front legs so that the seating surface may be changed from a substantially horizontal surface to a surface which slopes down slightly from front to rear.

Another object of my invention is to provide a couch with adjustable legs which legs are quick and easy to change from retracted to extended position, and from extended to retracted position.

Another object of my invention is to provide an adjustable leg which is simple and economical to manufacture and which is strong and reliable in use.

Another object of my invention is to provide an adjustable leg comprising a fixed member, a movable member pivoted to the fixed member, and means for maintaining the movable member in approximate alignment with the fixed member in all positions except when the movable member is in retracted position.

Another object of my invention is to provide an adjustable leg comprising a fixed member, a movable member pivoted to the fixed member, and spring means mounted on the movable member for urging the movable member into approximate alignment with the fixed member.

My invention has many other objects, advantages, and features, some of which, with the foregoing, will be set forth in the following description where I shall outline one form of my invention embodied in a studio couch, which I have selected for illustration in the drawings accompanying and forming a part of the present specification.

Referring to the drawings:

Fig. 1 is a perspective view, partly broken away, of a couch embodying the features of my invention;

Fig. 2 is a side elevational view of the frame and base of the couch shown in Fig. 1, and showing the adjustable legs in position when the couch is used for seating purposes;

Fig. 3 is another side elevational view of the frame and base of the couch shown in Fig. 1 when the couch is used for sleeping purposes;

2

Fig. 4 is an inside elevational view of one of the adjustable rear legs shown in Fig. 1;

Fig. 5 is a rear elevational view of the rear leg shown in Fig. 4 showing the leg in extended position;

Fig. 6 is a side elevational view of the rear leg taken as indicated in the direction of the arrow 6 in Fig. 5;

Fig. 7 is a transverse sectional view taken on the line 7—7 of Fig. 5; and

Fig. 8 is a perspective view, similar to Fig. 1, showing another arrangement of my invention.

Referring to Figs. 1, 2 and 3, the studio couch 10 comprises a frame 11, a base 12, springs 13, adjustable legs 14, fixed legs 15 having rollers 16, mattresses 17 and 18, and cushions 19. Obviously, the upper surface of the upper mattress 18 provides the seating surface 20, and the upper surface of the mattresses 17 and 18 as indicated in dotted lines in Fig. 3 provides the sleeping surface 20a.

The frame 11 and base 12 comprise front and rear members 21 and side members 22, all of which may be made of angle iron. The springs 13 are secured to the side members 22 and intermediate spring supporting members 23 are secured to the front and rear members 21. The base 12 is also provided with legs 24.

When the adjustable legs 14 are in retracted position, as shown in Figs. 1, 2 and 4, the seating surface 20 slopes down slightly from the front end of the couch to the rear. When the adjustable legs 14 are in extended position, as shown in Figs. 3, 5 and 6, the sleeping surface 20a is substantially horizontal.

As an instance of the construction of the adjustable legs 14, said legs 14 may comprise a fixed member 25 and a movable member 30.

The fixed member 25 may be made of angle iron and comprise rear 26 and side 27 portions, the upper ends of which are welded as at 28 or otherwise rigidly secured to the frame 11. A pin 29 is riveted or otherwise secured to the side portion 27.

The movable member 30 may also be made of angle iron and comprise rear 31 and side 32 portions. Means are provided to resiliently urge the movable member 30 in approximate alignment with the fixed member 25. For example, secured to the lower end of the inside of the rear portion 31 by means of a bolt 33 are leaf springs 34 which bear against the inside of the rear portion 26 of the fixed member 25. The leaf springs are spaced from the inside of the rear portion 31 by means of washers 35. The

side portion 32 is provided with a bayonet slot 36 and an elongated slot 37. A shaft 38 is secured to the lower end of the movable member 30 by means of brackets 39 and mounted on the shaft 38 is a roller 40.

The movable member 30 is pivoted to the lower end of the fixed member 25. As an instance of this arrangement, the side portion 32 of the movable member 30 is connected to the fixed member 25 by means of a pin 41 which extends through the elongated slot 37 and is riveted or otherwise secured to the lower end of the side portion 27. A washer 42 may be provided between the outer end of the pin 41 and the side portion 32.

The leaf springs 34 are mounted on the lower end of the inside of the rear portion 31 by means of the bolt 33 and washers 35 in such a manner that when the upper end of the movable member 30 is below the pin 29, the leaf springs maintain the movable member 30 in approximate alignment with the fixed member 25, as shown in Fig. 4. In this specification and the claims the expression "approximate alignment" of the movable member 30 with the fixed member 25 is used to mean that the positions of said members are such that as the couch 10 is lowered, the pin 29 of the fixed member 25 will be positioned in the bayonet slot 36 of the movable member 30.

The adjustable legs 14 are designed to be moved from their retracted position, as shown in Figs. 1, 2 and 4, through the intermediate position shown in dotted lines in Fig. 4 to their extended position shown in full lines in Figs. 3, 5 and 6, and are designed to be moved from their extended position shown in full lines in Figs. 3, 5 and 6, through the intermediate positions shown in dotted lines in Figs. 4 and 6, to their retracted position shown in Figs. 1, 2 and 4.

One manner by which the adjustable legs 14 may be moved from retracted to extended position is as follows: The corner of the couch 10 is raised to such an extent that the adjustable leg 14 is in the position shown in dotted lines in Fig. 4, that is, at least to such an extent that the pin 29 is above the upper edge of the movable member 30. As the couch is raised, the leaf springs 34 force the movable member 30 from horizontal to vertical position and maintain the movable member 30 in vertical position in approximate alignment with the fixed member 25, as shown in dotted lines in Fig. 4, so that when the couch is lowered the pin 29 will be positioned in the bayonet slot 36. The other adjustable leg 14 may then be moved from retracted to extended position in the same manner. As stated above, when the adjustable legs are in extended position, the surface 20 of the couch 10 is substantially level.

One manner by which the adjustable legs 14 may be moved from extended to retracted position is as follows: The corner of the couch 10 is raised until the upper edge of the movable member 30 is below the pin 29. If necessary, the movable member 30 is held so that it is not raised as the couch 10 is raised. An inward force, that is, a force against the action of the springs 34 is then applied to the lower rear portion 31 of the movable member 30. During the application of this inward force, which causes the movable member 30 to become out of approximate alignment with the supporting member 25, as shown in dotted lines in Fig. 6, the couch 10 is

lowered at least to such an extent that the pin 29 is below the upper edge of the movable member 30 in order to be certain that the pin 29 will not be positioned in the bayonet slot 36.

5 The inward force may then be released and the couch lowered to the floor, after which the adjustable leg 14 assumes the position shown in full lines in Fig. 4. The other adjustable leg 14 may then be moved from extended to retracted position in the same manner. As stated above, in this position, the surface 20 of the couch slopes down slightly from front to rear.

The couch is shown for use for sitting purposes in Fig. 1. In this position, with the adjustable legs 14 in retracted position, the couch is prevented from being rolled inadvertently. The couch may be prepared for sleeping purposes as a single bed either in that position, or after the adjustable legs 14 are moved from retracted to extended position.

When it is desired to prepare the couch for sleeping purposes, as a double bed, the adjustable legs 14 are moved from their retracted position to their extended position, thus placing the frame 11 and the mattresses 17 and 18 in a horizontal position. The frame 11 is then rolled from its position over the base 12 to the position adjacent the base 12, as shown in Fig. 3. Stops 43 are secured to the base 12 and are adapted to engage 30 one of the rear frame members 21 to limit the outward movement of the frame 11.

The mattress 18 is of greater thickness than the mattress 17 so that it may be moved from its position on the mattress 17 to the base 12 to thus provide the even horizontal sleeping surface 20a.

After use of the couch for sleeping purposes as a double bed, and when it is desired to prepare the couch for sitting purposes, the mattress 18 is moved from its position on the base 12 and placed on the mattress 17. The couch 10 is then rolled back over the base 12, after which the adjustable legs 14 are moved from their extended to their retracted positions.

45 In Fig. 8 a type of couch 10' is shown which may be used as a single bed. In this instance, the front legs are made adjustable. The seating surface 20b of the couch will be sloped down rearwardly when the adjustable legs 14' are in extended position and will be substantially level when the adjustable legs 14' are in retracted position. In said Fig. 8, like parts are indicated by like single primed reference numerals.

55 From the foregoing description taken in connection with the accompanying drawings, the uses, advantages and operation of my invention will be readily understood by those skilled in the art to which the invention appertains. While I have described one embodiment of my invention, I desire to have it understood that the form shown is merely illustrative and that the invention is not to be limited to the details disclosed herein, but is to be accorded the full scope of the appended claims.

60 65 I claim:

1. A couch comprising: a frame arranged to receive a seating surface for the couch; fixed legs; and adjustable legs movable from retracted to extended position, the seating surface of said couch being substantially horizontal when said adjustable legs are in one position, and said seating surface being sloped downwardly from the front toward the rear of said seating surface when said adjustable legs are in the other position, said adjustable legs comprising a fixed mem-

ber, a movable member pivoted to said fixed member and means for resiliently urging said movable member into approximate alignment with said fixed member.

2. A couch comprising: a frame arranged to receive a seating surface for the couch; fixed front legs; adjustable rear legs movable from retracted to extended position, the seating surface of said couch being substantially horizontal when said adjustable legs are in extended position, and said seating surface being sloped downwardly from the front toward the rear of said seating surface when said adjustable legs are in retracted position; and a resilient means adapted to apply a force to urge said adjustable legs from retracted to extended position when the couch is lifted.

3. A couch comprising: a frame arranged to receive a seating surface for the couch; fixed rear legs; and adjustable front legs movable from retracted to extended position, the seating surface of said couch being substantially horizontal when said adjustable legs are in retracted position, and said seating surface being sloped downwardly from the front toward the rear of said seating surface when said adjustable legs are in retracted position, said adjustable legs comprising a fixed member, a movable member pivoted to said fixed member and means for resiliently urging said movable member into approximate alignment with said fixed member.

4. A couch comprising: a frame arranged to receive a seating surface for the couch; fixed legs having rollers thereon; adjustable legs having rollers and being swingable from retracted to extended position, the seating surface of said couch being substantially horizontal when said adjustable legs are in one position, and said seating surface being sloped downwardly from the front toward the rear of said seating surface when said adjustable legs are in the other position; and spring means arranged to exert a force tending to swing said adjustable legs from retracted to extended position when said frame is lifted with relation to the floor.

5. A couch comprising: a frame; springs secured to said frame; a mattress providing a seating surface; fixed legs; and adjustable legs movable from retracted to extended position, the seating surface of said couch being substantially horizontal when said adjustable legs are in one position, and said seating surface being sloped downwardly from the front toward the rear of said seating surface when said adjustable legs are in the other position, said adjustable legs comprising a fixed member, a movable member pivoted to said fixed member and means for resiliently urging said movable member into approximate alignment with said fixed member.

6. A couch comprising: a frame; springs secured to said frame; a mattress providing a seating surface; fixed front legs; and adjustable rear legs movable from retracted to extended position, the seating surface of said couch being substantially horizontal when said adjustable legs are in extended position, and said seating surface being sloped downwardly from the front toward the rear of said seating surface when said adjustable legs are in retracted position, said adjustable legs comprising a fixed member, a movable member pivoted to said fixed member and means for resiliently urging said movable member into approximate alignment with said fixed member.

7. A couch comprising: a frame; springs secured to said frame; a mattress providing a seat-

ing surface; fixed rear legs; and adjustable front legs movable from retracted to extended position, the seating surface of said couch being substantially horizontal when said adjustable legs are in extended position, and said seating surface being sloped downwardly from the front toward the rear of said seating surface when said adjustable legs are in retracted position, said adjustable legs comprising a fixed member, a movable member pivoted to said fixed member and means for resiliently urging said movable member into approximate alignment with said fixed member.

8. A couch comprising: a frame; springs secured to said frame; a mattress providing a seating surface; fixed legs having rollers thereon; and adjustable legs having rollers and being movable from retracted to extended position, the seating surface of said couch being substantially horizontal when said adjustable legs are in one position, and said seating surface being sloped downwardly from the front toward the rear of said seating surface when said adjustable legs are in the other position, said adjustable legs comprising a fixed member, a movable member connected to said fixed member, said movable member being in alignment with said fixed member in extended position and normal to said fixed member in retracted position, means mounted on said movable member for resiliently urging said movable member from retracted to extended position and for resiliently urging said movable member into approximate alignment with said fixed member, and means for positively maintaining said movable member in alignment with said fixed member when said adjustable leg is in extended position.

9. An adjustable leg comprising: a fixed member; a movable member so that it may be swung from a position of approximate alignment with said fixed member to a lateral position pivoted to said fixed member; and means operatively connected to said members and acting when said movable member is in said lateral position to resiliently urge said movable member into approximate alignment with said fixed member.

10. An adjustable leg comprising: a fixed member; a movable member adapted to be swung from extended position to lateral position with relation to said fixed member, one of said members having an elongated slot, and the other of said members having a pin positioned through said elongated slot thereby pivotally mounting said movable member to said fixed member; and resilient means arranged so that it will apply a force to urge said movable member from said lateral position to said extended position with relation to said first member.

11. An adjustable leg comprising: a fixed member; a movable member having an elongated slot, said fixed member having a pin positioned through said elongated slot thereby mounting said movable member to said fixed member for movement from extended to retracted position with relation to said fixed member; and means adapted to resiliently urge said movable member from retracted to extended position.

12. An adjustable leg comprising: a fixed member; a movable member connected to said fixed member, said movable member being in alignment with said fixed member in extended position and normal to said fixed member in retracted position; and means mounted on said movable member positioned so that it will urge said mov-

able member from retracted to extended position and for resiliently urging said movable member into approximate alignment with said fixed member.

13. An adjustable leg comprising: a fixed member; a movable member connected to said fixed member, said movable member being in alignment with said fixed member in extended position and normal to said fixed member in retracted position; means mounted on said movable member for positioning so that it will urge said movable member from retracted to extended position and for resiliently urging said movable member into approximate alignment with said fixed member; and means for locking said movable member in alignment with said fixed member

when said adjustable leg is in extended position.
